US00D553994S

(12) **United States Design Patent** (10) **Patent No.:** **US D553,994 S**
Macak et al. (45) **Date of Patent:** **** Oct. 30, 2007**

(54) **CONTAINER**

(75) Inventors: **Donald F. Macak**, Chicago Ridge, IL (US); **Anne C. Plochman**, Lincolnshire, IL (US)

(73) Assignee: **Plochman, Inc.**, Manteno, IL (US)

(**) Term: **14 Years**

(21) Appl. No.: **29/268,171**

(22) Filed: **Oct. 31, 2006**

(51) LOC (8) Cl. **09-01**

(52) U.S. Cl. **D9/564**; D9/571; D9/574

(58) **Field of Classification Search** D9/447, D9/449, 450, 529, 542, 543, 544, 551, 558, D9/570, 572, 573, 574, 682, 685, 686, 687, D9/688, 689, 691, 692, 694; 220/660, 662, 220/675; 215/381, 382, 383, 384, 385, 12.1

See application file for complete search history.

CLAIM

The ornamental design for a container, as shown and described.

DESCRIPTION

FIG. 1 is a top, front, left perspective view of a container showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left elevational side view thereof;

FIG. 7 is a right elevational side view thereof; and,

FIG. 8 is a top, front, right side perspective view thereof.

The broken lines are for illustration purposes only and form no part of the claimed design.
